United States Patent Office

Des. 229,759

Patented Jan. 1, 1974

229,759

NONMONETARY COIN AND THE LIKE

Tomás Batista, San Juan, Puerto Rico, assignor to Del-Bros Jewelry Manufacturing Co., Inc., Bayamon, Puerto Rico

Filed June 16, 1971, Ser. No. 153,912

Term of patent 14 years

Int. Cl. D11—03

U.S. Cl. D29—19 R

The single figure is a plan view of a nonmonetary coin showing my new design, the side not shown being plain and the thickness being conventional.

I claim:

The ornamental design for a nonmonetary coin and the like, as shown and described.
